CLAIM

The ornamental design for a front panel for a processor
controller data processing system, as shown and de-
scribed.

DESCRIPTION

FIG. 1 is a front elevational view of a front panel for a
processor controller data processing system showing
my new design;

FIG. 2 is a right side elevational view thereof, the left
side elevational view being identical; and,

FIG. 3 is a top plan view thereof.

The rear elevational view is unornamented.

FIG. 3

FIG. 1

FIG. 2

UNITED STATES PATENT AND TRADEMARK OFFICE
CERTIFICATE OF CORRECTION

PATENT NO. : Des. 345,733
DATED : April 5, 1994
INVENTOR(S) : Wayne L. Aderman

It is certified that error appears in the above-identified patent and that said Letters Patent is hereby corrected as shown below:

On the Title page, col. 1, under Notice, should read --April 6, 2007--.

Signed and Sealed this

Thirtieth Day of August, 1994

Attest:

BRUCE LEHMAN

Attesting Officer

Commissioner of Patents and Trademarks
